UNITED STATES PATENT OFFICE.

THOMAS H. HILLEY, OF HUGO, INDIAN TERRITORY.

PLOW-HEEL.

No. 857,804.

Specification of Letters Patent.

Patented June 25, 1907.

Application filed March 26, 1907. Serial No. 364,692.

To all whom it may concern:

Be it known that I, THOMAS H. HILLEY, a citizen of the United States, residing at Hugo, in District 24, and Indian Territory, have invented a new and useful Plow-Heel, of which the following is a specification.

This invention has relation to adjustable plow heels and it consists in the novel construction and arrangement of its parts as 10 hereinafter shown and described.

The object of the invention is to provide a heel which is adapted to be applied to a plow standard and which may be adjusted in order to regulate the depth at which the 15 point will cut into the soil.

The heel consists primarily of a triangular frame the base of which is provided at its ends with curls to which the lower end of the sides are hinged. Means is provided for ad- 20 justably holding the upper ends of the sides together. The forward side is provided with an elongated slot which receives the heel bolt and by means of which the heel is fixed to the standard. The base of the triangle is 25 provided with a wear plate.

In the accompanying drawing:—Figure 1 is a side elevation of the heel applied to a plow standard, and Fig. 2 is a front elevation of the heel.

The heel consists of a triangular frame which is composed of the base 1 having at its end curls 2, 2. The lower ends of the sides 3 and 4 are hinged to the curls 2. The rear side 4 is substantially arcuate in edge elevation and is provided at its upper portion with an elongated slot 5. The forward upper surface of the side 4 in the vicinity of the slot 5 is roughened as at 6. The side 3 is provided

with an elongated slot 7 which is adapted to receive the heel bolt 8 by means of which the heel is attached to the plow standard. The upper end of the side 3 is rearwardly and downwardly curved and its rear surface is roughened as at 9. The bolt 10 passes transversely through the upper rear end of the 40 sides 3 and also through the slot 5 and is held by means of a nut bearing against the rear surface of the side 4. A wear plate 11 extends along the under surface of the base 1 and is held in position by the screws 11'.

From the foregoing description it is obvious that the heel may be adjusted longitudinally along the plow standard and that the angle of inclination of the base 1 with relation to the plow standard may be varied at 45 will by means of the elongated slot 5 pro- 50 vided at the upper portion of the side 4. When one wear plate 10 becomes worn out it may be readily removed and another sub- 55 stituted therefor.

Having described my invention what I claim as new and desire to secure by Letters- 60 Patent is:—

A plow heel comprising a base having at its ends upwardly disposed curls, sides 65 hinged to said curls and means for adjustably securing the upper ends of the sides together.

In testimony that I claim the foregoing as my own, I have hereto affixed my signature 70 in the presence of two witnesses.

THOMAS H. HILLEY.
